ARTIFICIAL-BAIT BOX

Hugh C. N. McGee, Dry Ridge, Ky.

Application February 8, 1954, Serial No. 28,905

Term of patent 14 years

(Cl. D58—12)

To all whom it may concern:

Be it known that I, Hugh C. N. McGee, a citizen of the United States, residing Dry Ridge, in the county of Grant and State of Kentucky, have invented a new, original, and ornamental Design for an Artificial-Bait Box, of which the following is a specification, reference being had to the accompanying drawing, forming a part thereof.

I claim:

The ornamental design for an artificial-bait box, substantially as shown.
